ACCESSORY CABINET FOR ELECTRONIC
CALCULATOR, OR THE LIKE

Barton D. Davis, Los Altos, Calif., and Donald P.
Aupperle, Loveland, Colo., assignors to Hewlett-
Packard Company, Palo Alto, Calif., a corporation
of California

Filed May 28, 1969, Ser. No. 17,398

Term of patent 14 years

Int. Cl. D14—02

U.S. Cl. D64—11

Figure 1

Figure 2

Figure 3

FIG. 1 is a front perspective view taken from the right side of an accessory cabinet for electronic calculator, or the like showing our new design;

FIG. 2 is another front perspective view taken from the left side thereof; and

FIG. 3 is a rear perspective view thereof.

The broken line representation of an electronic calculator in FIGS. 1 through 3 is for purposes of illustration only.

We claim:

The ornamental design for an accessory cabinet for electronic calculator, or the like, as shown and described.
